[57] CLAIM

The ornamental design for a toy Christmas carousel, as shown and described.

DESCRIPTION

FIG. 1 is a top, front and right side perspective view of a toy Christmas carousel according to my design;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and,

FIG. 7 is a bottom plan view thereof.

The shadows on the enclosed photographs cast in the photographic process are disclaimed and do not form part of the claimed design.
